PULVERIZING APPARATUS

Arthur C. Beardslee and Charles G. Clark,
Arcade, N. Y., assignors to The Borden Com-
pany, New York, N. Y., a corporation of New
Jersey

Application November 19, 1937, Serial No. 175,374

5 Claims.

(Cl. 83—11)

This invention relates to apparatus for pulverizing solid materials, such as dried milk products, which might be damaged by frictional heat.

Most pulverizing apparatus relies on the use of contact members to effect a cutting, grinding or abrasive action on the material to be pulverized. Heat destructible solids such as dried milk solids, casein, whey, or the like, frequently can be improved by further comminution but are seriously damaged if pulverized in the usual apparatus where considerable frictional heat is generated. In addition, such apparatus would usually be clogged by the treatment of products of this type.

It is an object of this invention to provide apparatus for pulverizing heat destructible solids to a fine state in an efficient manner without damage to such products.

Another object is the provision of pulverizing apparatus for heat destructible solids without damage thereto in which the capacity of the apparatus is increased for a given expenditure of power.

A further object of our invention is to provide a high speed centrifugal pulverizer of high capacity wherein the solids are moved at high velocity over and through a foraminous member, and admixed with heated air after passing through said member.

The invention will be more particularly described in connection with the embodiment thereof illustrated in the drawings, in which—

Figure 1 is a longitudinal vertical sectional view of pulverizing apparatus in accordance with our invention.

Figure 2 is a vertical sectional view through the first chamber of the apparatus and taken on the offset line 2—2 of Figure 1.

Figure 3 is a vertical sectional view through the second chamber of the apparatus and taken on the line 3—3 of Figure 1.

Figure 4 is a vertical sectional view taken through the feed hopper of the apparatus on the line 4—4 of Figure 1.

With reference to the drawings, the pulverizer housing includes a frame 10 supporting a circular casing 11. At one side, the casing 11 is provided with an integral bearing housing 13 and reinforcing flanges 11a; at the other side, casing 11 has a circular opening 12. The bearing housing 13 and flange 11a are preferably arranged eccentric to the circular casing 11 which has an integral tangential outlet 12a. Connected to casing 11, next to the opening 12, is an annular casing member 14 provided with a central opening 15 which communicates with opening 12, radially disposed webs 16 integral with the disc-shaped partition 17, and the annular ring 18. Integral with the casing member 14 is a circular shell 19. The annular casing member 14 with

webs 16, partition 17, ring 18 and shell 19 is preferably split horizontally into two halves which may be bolted together as shown at 19a. The lower half of member 14 may be supported on frame 10 by support 19b. Bolted to the annular ring 18, as by bolts 20, is a third casing member 21, provided with a hopper-shaped portion 22, a bearing housing 23, and the trough-shaped conduit portion 24 open at the inner end 10 25.

A shaft 26, carrying a drive pulley 27, is rotatably mounted in bearing housings 13 and 23 and extends through the casings 11, 14 and 21. Suitable ball bearings 28 for shaft 26 may be provided in the housing 13 and ball bearings 29 may also be employed in the housing 23. Lubricant such as grease may be retained in the bearing housings by grease retaining discs 30. Felt washers 30a also serve to retain lubricant and to cushion any axial thrust of the shaft 26. Shaft 26 may also be threaded near one end to receive nut 30b which together with collar 30c and shoulder 30d provides for adjustment of the end play of shaft 26. Fixed to shaft 26 in the trough portion 24 of casing member 21 is a helical feed screw 31 fixed to the shaft by a set screw 32.

Between partition 17 and the annular ring 18 an impeller 33 may be fixed to the shaft by the set screw 34. This impeller preferably comprises a hub portion 35 having an integral radially extending flange 36 which carries a series of impeller blades 37. The other ends of the impeller blades 37 may be fixed to the freely rotating annular disc 38. These impeller blades 37 are preferably relatively narrow and inclined rearwardly at a small angle with respect to a radius from the shaft 26. Radial flange 36 is preferably spaced a small distance from partition 17 and provided with integral fins 36a to prevent accumulation of material in said space. The impeller blades are also preferably closely adjacent to but not in contact with a circular screen 39 which may be formed of arcuate sections. These sections are clamped at one end between the annular ring 18 and the two semi-circular rings 40, having flanges 41 held between the ring 18 and the casing 21 by the bolts 20. At their other end, the screen sections are preferably supported on two semi-circular ring sections 42, said ring sections 42 being supported in notches (not shown) in the radial webs 16. Screen sections 39 are held rigidly in place and prevented from bulging outwardly by a pair of annular bands 43.

Inside the casing 11, a rotor 44 is fixed to shaft 26 by set screw 45. This rotor 44 may be constructed similar to impeller 33 with a radial flange 46 at one end, but carrying a plurality of blades 47 inclined forwardly with respect to the radius of the shaft 26. The blades may be

held in fixed relation to each other at their other ends by an annular ring 48.

The material to be pulverized may be introduced through a screen 49a in hopper 22 whence it is moved axially of shaft 26 by conveyor 31 through the opening 25 into the path of the impeller 33. Circular casing 19 preferably extends only part way from the annular wall of casing member 14 to the annular ring 18, thereby leaving an annular opening 49. A casing 50 is preferably provided around this opening 49 communicating with a supply conduit 51 and containing a suitable screen 52. Air may thus be supplied to the pulverizer through conduit 51, screen 52, and casing 50 where it sweeps over screen 39 and mingles with the pulverized material coming out through screen 39, thereafter passing in the direction of the arrows through the opening 15 to the rotor 44. The blades 47 of rotor 44 preferably extend a greater distance from shaft 26 than the impeller blades 37 to create a suction for assisting in the removal of material from screen 39. The blower or rotor 44 is also preferably arranged eccentrically with respect to the casing 11 so that the greatest space between the impeller blades 47 and the casing 11 occurs near the outlet 12a. Pulverized material may be discharged through the outlet 12a to a suitable dust collector or other device for separating solid material from the air. Heated air is preferably introduced through conduit 51 when material such as dried milk is being pulverized to provide a drying effect and also to prevent the pulverized solids from clogging screen 39.

The apparatus is preferably operated at high speeds of the order of 3600 R. P. M. to accomplish the pulverizing action and is particularly useful for pulverizing roller dried milk powder.

In the operation of the apparatus, material to be pulverized, such as roller dried milk powder is introduced into the hopper 22 through screen 49a and is conveyed by the helical screw 31 through opening 25 into the path of impeller 33. Blades 37 rapidly rotate the solid material throwing it outwardly by centrifugal force through the screen 39 and moving it over the inner surface of said screen 39. The fineness of the material may be varied by using screens of different mesh. Usual woven wire screens have been found to be suitable for this purpose.

Drying air, heated for example to a temperature of about 195° F. for roller dried milk, is introduced through conduit 51 and annular opening 49 to sweep over the outer surface of screen 39 in the direction of the arrows and exert a drying action on the freshly pulverized milk solids. The mixture of heated air and pulverized material then passes through the cylindrical casing member 19 and the opening 15 into the path of the rotor 44 where the pulverizing action is completed before the material is discharged through outlet 12a.

Little, if any air is mixed with the material fed through opening 25, thereby increasing the capacity of the impeller 33. By introducing warm air through conduit 51, the screen 39, the rotor 44, and the casing 11 are maintained relatively free from any coating of pulverized material which might impair the operation of the apparatus. In addition, the ultimate pulverized product has a lower moisture content than would otherwise be obtained.

By subjecting materials, such as roller dried

milk powder, first to the pulverization by attrition of the impeller 33 and screen 39 and thereafter mixed with warm air to the pulverization by impact of the rotor 44 in casing 11, it has been found that the best results are obtained.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention as claimed.

We claim:

1. Apparatus of the character described comprising a casing, an impeller arranged for rotation within said casing, a foraminous member in said casing surrounding and spaced from said impeller, means for feeding material to be pulverized into said impeller so that said material is forced through said member, and means for supplying and directing a current of air independent of any air passing through said member over substantially the entire outer surface of said member in a direction axially of said impeller.

2. A high speed centrifugal pulverizer comprising a casing, a rotary impeller within said casing having fixed blades disposed for movement in a direction approximately normal to their planes, a foraminous member surrounding and spaced from said impeller, a rotor comprising blades similar to the blades of said impeller, means for feeding material to be pulverized to said impeller, and means for conducting pulverized material passed through said member to said rotor, the blades of said impeller and of said rotor being inclined rearwardly and forwardly, respectively.

3. A high speed centrifugal pulverizer comprising a casing, a rotary impeller within said casing having blades for forcing material outwardly by centrifugal force, a shaft for rotating said impeller, a stationary screen surrounding said blades, a hopper associated with said casing, means for feeding material from the lower portion of said hopper along said shaft into the impeller, and means for supplying a current of drying air to the outer surface of said screen.

4. Apparatus of the character described comprising a casing, a shaft extending into said casing, an impeller having flat blades fixed to said shaft for rotation within said casing, a foraminous member in said casing surrounding and spaced from said impeller blades, a feed screw on said shaft for feeding material to be pulverized into a central portion of said impeller, and means for supplying a current of air to said material only after it has passed through said foraminous member.

5. A high speed centrifugal pulverizer comprising a casing, a shaft extending through said casing, a rotary impeller within said casing having blades fixed to said shaft for movement in a direction approximately normal to their planes, a foraminous member surrounding said impeller, a rotor comprising blades fixed to said shaft similar to said impeller blades, means fixed to said shaft for feeding material to be pulverized to a central portion of said impeller, means for conducting material passed through said foraminous member to a central portion of said rotor, and means for introducing a current of heated air into the material in said conducting means.
